CLAIM

The ornamental design for a cabinet speaker mount, as shown and described.

DESCRIPTION

FIG. 1 is a top-front-left perspective view of a cabinet speaker mount showing my new design;

FIG. 2 is a bottom-rear-right rear perspective view thereof;

FIG. 3 is an enlarged front elevational view thereof;

FIG. 4 is an enlarged rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a top-front-left perspective view of the cabinet speaker mount with a T-shaped coupler; and,

FIG. 10 is a bottom-rear-right perspective view of the cabinet speaker mount with the T-shaped coupler.

The broken line showing a T-shaped coupler in FIGS. 9 and 10 is included for the purpose of illustrating environmental structure and forms no part of the claimed design.
